UNITED STATES PATENT OFFICE.

DONALD M. TERRY, OF BROOKLYN, NEW YORK, ASSIGNOR TO WESTERN ELECTRIC COMPANY, INCORPORATED, OF NEW YORK, N. Y., A CORPORATION OF NEW YORK.

MEANS FOR PRODUCING OSCILLATIONS.

Application filed November 21, 1923. Serial No. 676,037.

To all whom it may concern:

Be it known that I, DONALD M. TERRY, a citizen of the United States of America, residing at Brooklyn, in the county of Kings 5 and State of New York, have invented certain new and useful Improvements in Means for Producing Oscillations, of which the following is a full, clear, concise, and exact description.

10 This invention relates to an arrangement for the production of oscillations, and more particularly to an arrangement including a three-electrode discharge device having its input and output circuits coupled in feed- 15 back relation to constitute an oscillator which is not sensitive to impedance changes in the circuits associated with the output terminals of the oscillator.

As is well known, electric discharge oscil- 20 lators are sensitive to impedance changes in the circuits associated with their output terminals. If the impedance of the load circuit coupled to an oscillator is varied, or the coupling means for supplying oscillations to 25 the load circuit is adjusted, both the frequency and the amplitude of the oscillations will be changed. This is due to the fact that the impedance changes react upon the frequency determining circuit of the oscillator.

30 To overcome this disadvantage, it has heretofore been proposed to include a reaction preventing device, i. e., either a large resistance or an asymmetrically conducting repeater between the load circuit and the 35 output terminals of the oscillator, whereby impedance changes are prevented from reacting upon the oscillator.

The present invention contemplates an arrangement in which the circuits associated 40 with the oscillating discharge device include means for preventing impedance changes in the load circuit coupled to the oscillator from reacting thereupon, whether these impedance changes are due to inherent condi- 45 tions in the load circuit itself, or to the adjustment of the coupling means for applying oscillations to the load circuit.

In accordance with the present invention 50 an electric discharge device has its input and output circuits coupled in feed back

relation to constitute an oscillator. The output circuit includes two oscillating current conducting paths. One output circuit includes a high feed back resistance, for limiting the operation of the device to the 55 linear portion of its characteristic curve representing the relation of input voltage to output current, connected in series with a frequency determining circuit. The other output branch includes a resistance connect- 60 ed in series with a means for coupling the oscillator to a load circuit. The function of the resistance included in the second output path is to stabilize the operation of the oscillator. 65

The input circuit of the oscillator includes a polarizing source which is adapted to impress a potential upon the control element of the discharge device of such a value that the control element is at all times negatively 70 polarized relatively to the cathode of the device.

By properly selecting the values of the resistances included in the two branches of the output circuit of the discharge device 75 relatively to the physical characteristics of the device and to each other and impressing a polarizing potential of suitable value on the grid of the device, an oscillator is provided which is adapted to generate an oscillating current of pure wave form and constant frequency, even though the impedances of the load circuit vary, and the coupling means is adjusted to change the amplitude of the current supplied to the load circuit. 80 85

The primary object of the present invention is to produce an oscillator which is not sensitive to impedance changes in the load circuit associated with it.

Another object is to produce an oscillator, 90 including a discharge device, adapted to supply constant frequency oscillations the amplitude of which may be varied within relatively wide limits.

A further object is an oscillating system 95 comprising a discharge device and associated circuits, adapted to produce oscillations of constant frequency, including means which permits the amplitude of the oscillations supplied by the system to a load circuit to 100

be varied over a wide range without changing their frequency.

For a complete understanding of the invention, reference may be made to the following specification read in conjunction with the attached drawing, in which Fig. 1 illustrates an oscillator embodying the invention and Fig. 2 shows an arrangement similar to that illustrated in Fig. 1 including 10 a different coupling means for transferring the oscillating current to a load circuit.

Referring to Fig. 1, there is shown an electric discharge device comprising a vessel 1 enclosing a cathode 2, an anode 3, and a 15 control electrode or grid 4. Heating current is supplied to the cathode 2 by the source 5. A source 6, having its negative terminal connected to the cathode 2 and its positive terminal connected to the anode 3 20 through a choke coil 7, supplies space current to the discharge device. The control electrode of the grid 4 is negatively polarized by a source 8 included in the circuit connecting the cathode and grid of the discharge 25 device, which also includes a coupling coil 9.

In addition to the space current path, the output circuit of the device is provided with two oscillating current paths. The first path extends from the anode 3 through the blocking condenser 10, the resistance 11, tuned 30 circuit 12 to the cathode 2. The circuit 12 serves to determine the frequency of the oscillations generated. The constants of circuit 12 may be varied by adjusting either 35 the inductance or capacity, as indicated by the arrows, or by adjusting both of these elements. The inductance coil included in the tuned circuit 12 is inductively associated with the coil 9, whereby energy is fed back 40 to the input circuit.

The second oscillating current output path may be traced from the anode 3 through the blocking condenser 10, resistance 13, potentiometer 14, cathode 2 and across the space 45 within the device to the anode 4.

By varying the position of the adjustable contact 15 associated with the resistance 14, the potential impressed upon the input circuits of the repeating device 16, and hence 50 the amplitude of the currents applied to the circuit 19, may be regulated.

The arrangement illustrated in Fig. 2 is similar to that described above. An electric discharge device 1 is provided with an 55 input circuit connecting its cathode 2 and control electrode 4. The input circuit includes the polarizing source 8 and coupling coil 9. The output circuit, in addition to the space current path including source 6 60 and choke coil 7, is provided with two branches through which oscillating current flows. One oscillating current branch, extending from the cathode 2 to the anode 3, includes blocking condenser 10, feed back 65 resistance 11, and frequency determining cir-

cuit 12. The inductance coil of the frequency determining circuit is inductively associated with the coil 9 included in the output circuit. By means of this coupling oscillating current of a frequency determined by the 70 constants of the circuit 12 is fed back to the input circuit to control the production of oscillations. The other oscillating currents branch includes a resistance 13 and the primary winding of the repeating coil or transformer 22, which serves to connect the oscillator to a load circuit 23.

In order to produce oscillating current of sinusoidal wave form of the frequency determined by the constant of the circuit 12, 80 the resistance 11 should be sufficiently large to limit the amplitude of the generated waves to such a value that the device operates on the most nearly linear portion of its characteristic curve representing the relation between input voltage and output current. Again, the inductance coil included in the frequency determining circuit 12 should be so designed that the ratio of its inductance to its resistance should be large and the coefficient of coupling between this coil and the coil 9 should also be large.

The negative potential normally impressed upon the grid of the discharge device should be of such value that under all operating 95 conditions the grid of the oscillating device is never permitted to become positive relatively to its cathode.

With a circuit designed to meet the conditions outlined above and having the impedances of the two branches of the output circuit associated with the device properly proportioned, it has been found that the operation of the oscillator is so stable that the amplitude of the oscillations supplied to the 100 load circuit through the potentiometer or coupling transformer may be varied over a wide range without causing an appreciable change in the frequency of the oscillations produced by the oscillator. Hence, by choosing the resistance 13 included in the load coupling branch of the output circuit, such that the impedance of this branch bears a definite relation to the impedance of the feed back branch, including the resistance 11 105 and the frequency determining circuit 12, it is possible to provide an oscillator adapted to supply oscillations of constant frequency and adjustable amplitude to a load circuit.

Experiments have been made with an oscillator of the design described above adapted to produce oscillations of 3330 cycles, which includes an electric discharge device having physical characteristics such that 115 when a heating current of 1.3 amperes is supplied to its cathode, a potential of 120 volts is impressed upon its plate electrode, and a polarizing potential of 4.5 volts is impressed upon its grid, the internal plate 120 130

circuit impedance of the device is of the order of 6000 ohms. A feed back resistance of 230,000 ohms was used, the time constant of the coil included in the frequency determining circuit as identified by the fraction

$$\frac{\omega L}{R}$$

- 10 (where $\omega = 2\pi f$, L = inductance and R = resistance) was 77, the coefficient of coupling was about .95 and the load coupling branch included a resistance of 96,000 ohms and a potentiometer of 16,000 ohms.
- 15 When the filament heating current was changed from 1.2 to 1.4 amperes, the frequency of the oscillations produced varied .021 per cent. Changing the plate voltage from 100 to 140 volts caused the frequency 20 of the oscillations to vary .012 per cent, and when the potentiometer was adjusted over its complete range, whereby the amplitude of the oscillations supplied to the load circuit was varied from zero to 10 milli- 25 amperes, it was impossible to detect any change in the frequency of the oscillations generated.

It will therefore be seen that this invention provides an oscillator, comprising a single electric discharge device and its associated circuits, which, while permitting the value of the oscillating energy available at its output terminals for transmission to a load circuit to be adjusted over a wide range, 30 is as stable or even more stable than electric discharge oscillators hitherto proposed.

Thus, in the arrangement described above the output terminals of the oscillator may be directly associated with a load circuit and 40 great flexibility is permitted in adjusting the value of the oscillating energy supplied to a load circuit without introducing disturbing reactions into the oscillator circuits.

While in the preceding description specific arrangements and details have been set forth for the purpose of completely disclosing the nature of the present invention, it is to be understood that this invention is not limited to the details of the circuits and apparatus disclosed, but only by the scope of 50 the attached claims.

What is claimed is:

1. An oscillation generator comprising an electric discharge device having a cathode, 55 an anode and a grid, input and output circuits connected in feed back relation to generate oscillations of constant frequency, said output circuit having a plurality of oscillating current paths, one of said paths constituting a feed back path coupled to said input circuit, means included in each of the oscillating current paths of said circuits for stabilizing the operation of the oscillator, and adjustable coupling means for varying 60 the value of the constant frequency oscillat-

ing energy available at the output terminals of the oscillator for transmission to a load circuit.

2. An oscillation generator comprising an electric discharge device having a cathode, 70 an anode and a grid, input and output circuits connected in feed back relation to produce oscillations of constant frequency, means for maintaining the grid of said device at all times negatively polarized relatively to 75 its cathode, an output oscillating current branch including a frequency determining circuit and a stabilizing impedance, a second output oscillating current branch including stabilizing means and adjustable means for 80 coupling the oscillator to a load circuit, whereby the constant frequency oscillating energy available for transmission to a load circuit may be varied.

3. An oscillation generator comprising an electric discharge device having a cathode, an anode and a control electrode, and input and output circuits therefor, the output circuit including two parallel connected branches, one of which includes a high resistance and is coupled to the input circuit to control the production of oscillations, and the other branch includes a stabilizing resistance and also means for coupling the oscillator to a load circuit. 85

4. An oscillation generator comprising an electric discharge device having a cathode, an anode and a control electrode, input and output circuits therefor coupled in feed back relation, a feed back path including 100 a frequency determining circuit and a resistance in series therewith, a second oscillating current path connected in parallel with the feed back path and including coupling means for a load circuit and a stabilizing resistance. 105

5. An oscillation generator comprising an electric discharge device having a cathode, an anode and a control electrode, input and output circuits therefor coupled in feed back 110 relation, said input circuit including a source for maintaining the control electrode at all times negatively polarized relatively to said cathode, a feed back path including a frequency determining circuit and a resistance 115 in series therewith, a second oscillating current path connected in parallel with the feed back path and including coupling means for a load circuit and a stabilizing resistance.

6. An oscillation generator comprising an electric discharge device having a cathode, an anode and a control electrode, input and output circuits therefor coupled in feed back relation, a feed back path including a frequency determining circuit and a resistance, a second oscillating current path including coupling means for a load circuit and a resistance, the ratio of the impedance of the feed back path to that of the load circuit 125 coupling path being substantially fixed. 130

7. A space discharge oscillator comprising a grid circuit containing a coupling coil, an anode-cathode path containing a direct current source and an inductance of high value, another anode-cathode path containing a condenser, a resistance and a tuned loop in series, the inductance of said loop being coupled to said grid circuit coil, a coupling path from the junction point of said condenser and resistance to said cathode, said coupling path including large

ohmic resistance, and a load circuit coupled to other impedance means in said coupling path.

8. A combination in accordance with claim 7 in which said other impedance means is a resistance of relatively small value.

In witness whereof, I hereunto subscribe my name this 14th day of November, A. D. 1923.

DONALD M. TERRY.
